UNITED STATES PATENT OFFICE.

CLAUDE A. CONOVER, OF NEWBURGH, NEW YORK.

DENTAL DAM-HOLDER.

No. 888,310.

Specification of Letters Patent.

Patented May 19, 1908.

Application filed June 3, 1907. Serial No. 377,066.

To all whom it may concern:

Be it known that I, CLAUDE A. CONOVER, a citizen of the United States, and a resident of Newburgh, in the county of Orange and 5 State of New York, have invented a new and useful Improvement in Dental Dam-Holders, of which the following is a full, clear, and exact description.

The purpose of the invention is to so construct a rubber dam holder for dentists' use, that the frame will be flexible and provided with removable rubber pads or facings adapted to lie next the face, thus rendering the holder cool and comfortable to the wearer, 15 and enabling the dentist to remove and sterilize the pads each time the device is used.

The invention consists in the novel construction and combination of the several parts, as will be hereinafter fully set forth 20 and pointed out in the claims.

Reference is to be had to the accompanying drawings forming a part of this specification, in which similar characters of reference indicate corresponding parts in all the figures.

Figure 1 is a side elevation of the improved dam holder applied; Fig. 2 is an enlarged horizontal section through one of the cheek pieces or frames of the holders and its accompanying pad, the section being taken practically on the line 2—2 of Fig. 3; and Fig. 3 is an inner face view of one of the pads for the frame or cheek piece.

The device consists primarily of opposing 35 frames or cheek pieces A, and accompanying pads or linings B for the inner faces of the said frames or cheek pieces. The frames or cheek pieces A are made of thin sheet brass, or other metal, so that they are more or less 40 flexible, contributing thereby to the comfort of the wearer, and in order that the said frames or cheek pieces may be as light as possible they are of skeleton formation, as is illustrated, although they may be made without 45 the opening shown therein. Preferably these frames or cheek pieces A are substantially triangular in shape, their wider ends facing to the front, and also preferably the lower corners of the said frames or cheek 50 pieces extend forwardly beyond the upper corresponding corners, and at the upper and lower forward corners of each cheek piece or frame A, a clip 10 of any suitable construc-

tion is applied, being secured to the frame or cheek pieces in any approved manner. 55 These clips 10 are adapted to take hold of the end portions of a rubber dam 11 when the device is in use, as is illustrated in Fig. 1.

A pad B is located at the inner face of each frame or cheek piece A, and while these pads 60 are preferably made of rubber, they may be made of any smooth and flexible material. The pads B, by preference, conform to the contour of the cheek pieces or frames to which they are attached, but are of larger 65 size so as to extend beyond the edges of the cheek pieces or frames in order to prevent said edges from coming in contact with the face of the wearer of the device. The cheek pieces or frames A may be straight, but by 70 preference they are given a slight curvature, their inner surfaces being more or less concaved. The pads B are removably attached to the cheek pieces or frames A, in order that the pads may be removed whenever it is 75 thought desirable to sterilize them, since the pads come directly in contact with the face of the wearer of the device.

The connection between the pads B and the cheek pieces or frames A may be made in 80 many ways; by preference, however, the connection is effected as is shown in the accompanying drawings, wherein separable buttons C are employed, and usually the socket members 12 of these buttons are secured to the outer faces of the pads B, while the entering or post members 13 are secured to the inner faces of the cheek pieces or frames A. Thus it will be observed that a ready 85 attachment may be effected between a pad 90 and a frame, or the two said parts may be conveniently and expeditiously separated. The cheek pieces or frames and their accompanying pads are connected by an elastic tape 14, or its equivalent, the ends whereof 95 are passed through suitable slots or openings 15 in the rear end portions of the frames or cheek pieces A, as is illustrated in Figs. 1 and 2, and one or both ends of the said tape 14 adjustably secured in any approved manner. 100

In operation the frames and their pads are located at the outer surface of each cheek of the face of the wearer, while the elastic connecting band or tape 14 is passed around the head of the wearer at the rear, as is shown in 105 Fig. 1.

Having thus described my invention, I claim as new and desire to secure by Letters Patent,—

A dental dam holder having detachable 5 pads of a yielding material adapted for engagement with the face of the wearer.

In testimony whereof I have signed my

name to this specification in the presence of two subscribing witnesses.

CLAUDE A. CONOVER.
